UNITED STATES PATENT OFFICE.

SOLOMON WISE, OF CINCINNATI, OHIO.

DESIGN FOR A LOCK FOR SPARE RIMS AND TIRES.

Application filed January 2, 1929. Serial No. 29,480. Term of patent 14 years.

To all whom it may concern:

Be it known that I, SOLOMON WISE, a citizen of the United States, residing at Cincinnati, in the county of Hamilton and State of Ohio, have invented a new, original, and ornamental Design for Locks for Spare Rims and Tires, of which the following is a specification, reference being had to the accompanying drawing, forming part thereof.

In the drawing:

The figure is a perspective view of the lock, showing my new design.

I claim:

The ornamental design for a lock for spare rims and tires substantially as shown.

SOLOMON WISE.
